CLAIM

The ornamental design for a wine rack, as shown.

DESCRIPTION

FIG. 1 is a perspective view of a four-channel wine rack;
FIG. 2 is a perspective view of a six-channel wine rack;
FIG. 3 is a perspective view of an eight-channel wine rack;
FIG. 4 is a perspective view of a 10-channel wine rack;
FIG. 5 is a perspective view of a 12-channel wine rack;
FIG. 6 is a front view of a four-channel wine rack;
FIG. 7 is a back view of a four-channel wine rack;
FIG. 8 is a side view of a four-channel wine rack;
FIG. 9 is a side view of a four-channel wine rack;
FIG. 10 is a front view of a six-channel wine rack;
FIG. 11 is a back view of a six-channel wine rack;
FIG. 12 is a side view of a six-channel wine rack;
FIG. 13 is a side view of a six-channel wine rack;
FIG. 14 is a front view of an eight-channel wine rack;
FIG. 15 is a back view of an eight-channel wine rack;
FIG. 16 is a side view of an eight-channel wine rack;
FIG. 17 is a side view of an eight-channel wine rack;
FIG. 18 is a front view of a 10-channel wine rack;
FIG. 19 is a back view of a 10-channel wine rack;
FIG. 20 is a side view of a 10-channel wine rack;
FIG. 21 is a side view of a 10-channel wine rack;
FIG. 22 is a front view of a 12-channel wine rack;
FIG. 23 is a back view of a 12-channel wine rack;
FIG. 24 is a side view of a 12-channel wine rack;
FIG. 25 is a side view of a 12-channel wine rack;
FIG. 26 is a top view of the wine rack; and,
FIG. 27 is a bottom view of the wine rack.
